Reddick, Schmitt

UNITED STATES PATENT OFFICE.

CHARLES EDWIN HAMILTON, OF TROY, NEW YORK.

IRONING PAD.

Application filed April 12, 1921, Serial No. 460,696. Renewed December 13, 1922.

To all whom it may concern:

Be it known that I, CHARLES EDWIN HAMILTON, a citizen of the United States, and a resident of Troy, in the county of 5 Rensselaer and State of New York, have invented certain new and useful Improvements in Ironing Pads, of which the following is a specification.

The invention relates to ironing pads as 10 employed in ironing tables for pressing or in ironing machines; and more particularly to a resilient pad such as is set forth in United States Letters Patent No. 1,054,407, granted me the 25th day of February, 1913.

15 The pad disclosed in said patent consists substantially of a base plate upon which are secured a plurality of adjacent springs, the latter being covered by suitable caps which support a fabric top. In the use of 20 these springs, particularly with pads of inclined or cylindrical shape, difficulty has been experienced in retaining the frictionally held caps to the spring ends; and, when a bottom cap is also employed, of retaining the spring in the said bottom cap. 25 It is the object of the present invention to so construct a cap that while the same may conveniently be attached and removed from the spring member, yet it may be held thereto in manner to prevent its accidental detachment therefrom. This feature is especially valuable in assembling the pad or 30 in replacing worn springs or caps.

In the accompanying drawings which 35 illustrate the invention—

Fig. 1 shows a pad as employed in connection with a cuff pressing machine having inclined platen.

Fig. 2 is a view showing the arrangement 40 of the capped springs on a cylindrical type of machine.

Fig. 3 is a perspective detail view, partly in section, of a spring and caps therefor.

Similar characters of reference designate 45 corresponding parts throughout the several views.

Referring to the drawings, the pad may be of various shapes, for example inclined as shown in Fig. 1; or, cylindrical, as shown

in Fig. 2. It is these particular forms of 50 pad that introduce the greatest difficulty with the type of capped springs set forth in my aforesaid patent, the pad being composed of a base plate 10, which supports a plurality of coil springs 11, inner caps 12 being preferably provided and into which the 55 said springs are seated. The outer end of a spring 11 is capped with a similar cap 13 and over the entire flexible surface is provided a top of fabric or like material 14, the 60 same being supported by said caps and springs.

In accordance with the present invention, the caps are provided with means which will engage with the turns of a spring to securely 65 retain thereby a cap to its said spring. For example, the side wall of a cap may be indented or provided with an inwardly directed projection 15 which is designed to extend under a turn of the spring and to allow 70 of the cap being screwed on the end thereof; and, similarly removed therefrom when desired. So long, however, as a cap is thus seated on its spring, it will be securely retained thereto by the inwardly directed projection 75 15 engaging the said turn. It will be understood that both the inner and outer caps will be provided with such engaging means and it will be found that there will be practically no loosening of these caps 80 after the same are once in place. The assembling of a pad is thereby greatly facilitated; and no damage is likely to result to the pad, as has been the case heretofore, in 85 that springs have worked loose from their base caps as well as outer caps themselves having come loose from a spring.

I claim:—

In an ironing pad of the character set forth: a coil spring, and a cap therefor 90 located about an end thereof, the wall of said cap being indented to provide an inwardly directed projection for engaging the turns of the spring to secure the cap thereon.

Signed at New York in the county of 95 New York and State of New York this 11th day of April, A. D. 1921.

C. EDWIN HAMILTON.
